Fig. 4

Fig. 5

FIGURE 1 is a front view of a golf club head showing my new design;

FIG. 2 is a side view of the golf club head;

FIG. 3 is a top view of the golf club head;

FIG. 4 is a rear view of the golf club head taken on the line 4—4 of FIG. 2; and

FIG. 5 is a back view of the club looking from the left in FIG. 4.

The dominant features of my design reside in the portions shown in full lines, the blade for the head being characterized by the flat back thereof having the end portion rounded and extending from the face to the back surface of the club inwardly from the end thereof and merging with a slightly projecting rib forming a continuation of the bottom surface of the blade, said back having a shallow transverse recess at the top edge extending across the back and partially around the hosel for the club, all as shown.

I claim:

The ornamental design for a golf club head, as shown and described.
